UNITED STATES PATENT OFFICE.

THOMAS BEESLEY, OF MUSCATINE, IOWA.

CALORIC-ENGINE.

SPECIFICATION forming part of Letters Patent No. 270,000, dated January 2, 1883.

Application filed April 19, 1882. (No model.)

To all whom it may concern:

Be it known that I, THOMAS BEESLEY, of Muscatine, in the county of Muscatine and State of Iowa, have invented a new and useful Improvement in Engines; of which the following is a full, clear, and exact description.

My invention relates to the application of force generated by expansion of air and water by electric currents, said force being utilized for action on a piston fitted for reciprocation in a cylinder, suitable pumps, valves, compression and generating chambers, and a governor, all as set forth particularly hereinafter and claimed.

Reference is to be had to the accompanying drawings, forming part of this specification, in which similar letters of reference indicate corresponding parts in all the figures.

Figure 1 is a sectional side elevation of the engine. Fig. 2 is a plan view. Fig. 3 is an end view at the crank-shaft. Fig. 4 is an end view at the cylinder ends in larger size and with the plate removed to expose the chambers. Fig. 5 is a face view of the valve mechanism in larger size, showing also the connections for supply of gas when such is desired. Fig. 6 is an end view of the main cylinder with the head removed. Fig. 7 shows the main valves. Fig. 8 is a detail of the gas-supply devices, which I reserve the right to claim in a separate application. Fig. 9 is a detail view of the mechanism for operating the air-supply valves, and Figs. 10, 11, and 12 are detail views of the governor. Fig. 13 shows the main slide-valve.

A is the bed-plate, of suitable character, supporting a crank-shaft, *a*, on pillow-blocks *b*.

B is the main cylinder, provided with piston *c* and rod *d*, connected to a cross-head, *e*, that is fitted on slideways *f*. *g* is a rod connecting from slide *e* to the crank-shaft *a*.

C is the cylinder of the air-pump on the bed-plate A, below the main cylinder B, provided with piston *h* and a rod, *i*, that connects to a slide, *k*, a rock-lever pivoted on the bed-plate, and connecting by a rod, *m*, to slide *k*, and also by a rod, *n*, to a crank-disk on a secondary shaft, *p*, sustained on pillow-blocks *b*, on which is a wheel, *o*, gearing with a larger wheel, *q*,

on the main crank-shaft *a*, whereby the shaft *p* is caused to make two revolutions to one of

the main shaft. The rod *n* connects to the crank-pin of rock-lever *l* by an open hook, which allows its ready disconnection, and the lever has an aperture to receive a hand-bar for use to operate the air-pump by hand in starting the engine.

The pump-cylinder C is formed at its ends with compression-chambers *r*, communicating with the interior of the cylinder by openings that are fitted with disk-valves *s*, closed by springs. Inlet-pipes *t*, with suitable valves, are also fitted in connection with the cylinder.

Above the compression-chambers *r* are generating-chambers *u*, communicating therewith by openings, above which are raised valve-seats *v*, having side openings. Upon the valve-seats *v* are slide-valves *w*, attached to plates on the ends of rods *y*, that pass through the heads of chambers *u*, above which the rods are connected to the ends of rock-levers *a'*. A shaft, *b'*, sustained in suitable bearings at the side of cylinder B, carries cams *c' c'*, that act on rods *d' d'* from the ends of levers *a'*, whereby the valves *w* are moved down to close the outlets in valve-faces *v*, the return movement being given by spiral springs on rods *d'*. (See detail, Fig. 9.) The shaft *b'* extends to the secondary shaft *p*, where it carries a bevel-pinion, *e'*, that engages a similar pinion on shaft *p*, so that the shaft *b'* is rotated and the valves *w* opened in proper time and order.

Above the chambers *r* are water-pumps *f'*, provided with plungers *g'*, which, as shown most clearly in Fig. 5, are suspended from elbow-levers *h'*, that are connected for simultaneous movement by a rod, *i'*. One lever *h'* is connected by a rod, *k'*, to the strap of an eccentric, *l'*, on main shaft *a* for operation of plungers *g'*. Service-pipes *m'* from a suitable source of water-supply connect to pumps *f'*, and in the pipes *m'* are regulating-valves *n'*. From the pumps pipes *o'* pass to the generating-chambers *u*. The main valve-chambers are at *p' p'*, on one side of the main cylinder B, and communicate directly with the generating-chambers *u*.

q', Figs. 1 and 5, are the ports from the chamber *p'* to cylinder B, and *r'* are the exhaust-ports of the chamber.

The slide-valves *s'* (shown separately in Figs. 7 and 13) are connected by a valve-rod, *t'*, which

is operated by a connecting-rod, u' , from an eccentric, v' , on main shaft a . Fig. 13 shows the packings of the slide-valve, which consist of plates S^4 , pressed to the valve by springs S^5 , that are behind the plates in holes formed in the cover and one end of the chest, set-screws S^6 being provided to regulate the tension of the springs.

The construction so far as described provides for supply of air and water to the generating-chambers. For heating and expanding the air and converting the water to steam I use an electric arc in the generating-chamber, as next described.

15 $a^2 a^3$, Figs. 4 and 5, are tubes of non-conducting material extending through the sides of the generating-chambers, and fitted with carbons b^2 , that are to be connected outside the chambers with a battery or dynamo-electric machine of suitable power.

c^2 are perforated plates in the chambers above the carbon points and below the water-supply pipes o' , so as to receive the water and act as screens and finely divide it. Suitable feeding and regulating devices are provided in connection with the carbons.

I also provide for regulating the flow of water to the generating-chamber by automatic governing mechanism shown in Figs. 1, 2, and

30 10, and consisting as follows:

E is a governor of the centrifugal type, fixed on cylinder B, of which d^2 is the sliding stem, moved by the arms and balls.

l^2 is a valve-stem supported at its ends in 35 valve-chambers f^2 , and provided with an arm, g^2 , to which the stem d^2 is connected. The valve-chambers f^2 are placed between the pumps f' and the ends of service-pipes m' , (see Figs. 1 and 11,) so that the water going 40 to the pumps shall pass through the chambers, and the ends of stem l^2 cover the inlet of the service-pipes to the chamber. The stem is hollowed out and slotted at h^2 to register with the inlets to the chamber, so that the inlet 45 shall be increased and decreased by the rocking motion of the valve-stem given to it by the governor E.

For regulating the amount of air pumped at each stroke of the air-pump, and consequently regulating the pressure in chamber, I provide for varying the stroke of the pump-piston h by means of a hand-wheel and screw, i^2 , on the rock-lever l , connected to a slide on the lever that carries the wrist-pin of the rod n .

55 The operation is as follows: To start the engine, rod n is to be unhooked and the rock-lever l worked by a hand-bar to operate the pump C and force air into the compression-chambers r and generators u . The electric 60 current is next put on to the carbons, and, the arc being formed, the compressed air is heated, after which rod n is to be connected for work. The rod k' is then to be unhooked from the pump-levers h' , so that the pumps f' can be 65 worked by hand. Service-valves n' are to be opened, thereby allowing water to pass to valve-

70 chambers f^2 , and the pumps being operated, the water goes by pipes o' to the generating-chambers u , and, dropping upon the perforated plates c^2 , is instantly converted to steam. Rod k' is then replaced and rod u' of the slide-valves disconnected, and the engine is ready to start in either direction as the valve-rod t' may be moved. Any desired pressure may be got before starting the engine, and the water may be 75 heated before being passed to the pumps by using exhaust-steam in any suitable manner. The air-pump makes two full strokes to every one of the main piston. The outlet-valves s of the air-pump close and the valves w open before the stroke of the main piston is completed, and the water is injected into the generator at the same moment, so that there is time for the expansion of the air and conversion of the water to steam before the main valve s' opens, 80 the operation being the same at each end.

In place of supplying jets of water to the generator, or in connection with the water, explosive gases, gasoline, or crude petroleum 85 may be injected.

90 For supplying gasoline or other explosive liquid I connect the supply-pipes to the service-valves n' and the liquid passed in with the water for conversion to gas by the electric heat.

95 To supply gas I connect a pipe from a gasometer to cocks $l^3 l^3$, that are attached to the sides of the generating-chambers, (see Fig. 5,) and from the cocks l^3 flexible tubes m^2 pass to service-valves n' . A compression-bar, n^2 , Figs. 100 5 and 8, connected to the rod t' of the main valves, so as to move with the valves, extends to the flexible tubes m^2 and acts to compress them alternately against the fixed lugs o^2 , and thus cut off the supply of gas to the service-valves n' . In the ends of bar n^2 are fitted blocks p^2 , of hard rubber, projected by spiral springs q^2 , the object being to retain the flexible tubes compressed after the bar starts back.

105 r^2 is the stem of the two gas-cocks r^3 , provided with an arm, s^2 , that is connected by a link, t^2 , with the arm g^2 of the governing valve-stem l^2 , so that the governor E shall regulate the gas and the water supply simultaneously.

110 By this construction I combine for the operation of the engine the forces of compressed and heated air, steam, and explosive gases, electricity being the converting force that brings the combined forces into action.

115 I may dispense with either water or gas in the combination, as found most convenient, and the air, water, and gases are to be supplied in any suitable proportions.

120 It will be understood that I reserve the right to claim in a separate application the devices for feeding or supplying gases to the engine.

Having thus fully described my invention, I claim as new and desire to secure by Letters Patent—

130 1. In engines, the combination of a pump for supplying water in jets and a pump for supplying compressed air with a generating-

chamber heated by an electric current, substantially as shown and described, whereby a force is generated by expansion of the air and conversion of the water to steam for operating the engine.

2. In combination with the engine-cylinder B, provided with valve-case p' , the generating-chambers u , air-pump C, water-pumps f' , provided with suitable valves, and the carbons b^2 , connected in electric circuit, substantially as shown and described.

3. The combination, in generator u , of the carbons b^2 , perforated plate c^2 , and water-supply pipe o' , substantially as shown and described.

4. The combination of valve w , valve-seat v , and water-supply o' with the compression-chamber r and generator u , substantially as described.

5. The combination, with an engine-cylinder, of a generating-chamber at each end, heated

by an electric current, and supplied with jets of air and steam intermittently and in succession, substantially as shown and described.

6. The pumps f' and water-supply pipes $m' o'$, combined with the generating-chamber u , substantially as shown and described.

7. The governor E, valve-stem l^2 , chamber f^2 , water-pipes m' , and pumps f' , substantially as described, combined for operation as set forth.

8. The combination of valve-chest p' , valve s' , generator u , and engine-cylinder B, substantially as shown and described.

9. The combination of the rocking lever l , screw i^2 , carrying a wrist-pin, rod m , connected to the pump-slide, and the reciprocating rod n , substantially as shown and described.

THOMAS BEESLEY.
